UNITED STATES PATENT OFFICE.

WILLIAM A. GEIGER, OF CHICAGO, ILLINOIS, ASSIGNOR TO W. H. MINER, INC.,
OF CHICAGO, ILLINOIS, A CORPORATION OF DELAWARE.

ANTIFRICTION BEARING.

Application filed February 5, 1926. Serial No. 86,169.

This invention relates to anti-friction bearings.

disposed side walls 20-20, end walls 21-21 and a bottom 22, said bottom being provided with recesses 23-23 on its under surface to accommodate the heads 24-24 of rivets 25-25 which extend through the bottom 22 and through a bearing plate 26, thereby securing the bearing plate to the bottom 22. The housing is also provided with laterally extending flange portions 27-27 at each end thereof which are secured to the top plate of the truck bolster 11 by means of rivets 28-28. The inner surface of each of the end walls is provided with a pair of spaced ribs 29-29, which extend inwardly toward the ends of the bearing plate 26, and the faces of said ribs are curved as indicated at 30 in conformance with the curvature of the anti-friction element, said ribs serving as stops to limit the movement of the anti-friction element at either side of its central position.

The anti-friction element B, as shown, is in the form of a plain cylindrical roller which is adapted to move longitudinally with reference to the housing upon the bearing plate 26. 80

The centering and retaining devices C—C are identically similar in construction, except for their opposite disposition, one of the same being disposed at one end of the housing at one side of the roller, and the other being disposed at the other end of the

housing at the opposite side of said roller. Each centering mechanism C comprises generally a bearing portion or pocket 31, spring 90 32 and transmitting member 33. The pocket 31, as shown, is in the form of a centrally disposed cylindrical extension formed as an offset of the end wall 21, the central axis of the cylindrical extension being arranged in a plane above the central axis of the roller B. The pocket has an outer wall 34 and opens inwardly toward the roller B, the mouth of the pocket being constricted by portions 35—35 which form diametrically 100

disposed upper and lower segmental abutments. The transmitting member 33 is a cup shaped formation, having a spring receiving socket 36, and the cylindrical wall of said member is provided at its open end 105 with diametrically arranged segmental extensions providing abutments 37-37, said abutments being of such character that the same may be inserted through the gaps between the abutments 25 after the soiled

The housing or retainer A, as shown, is of rectangular formation having vertically

spring 32 has been disposed in the socket 36, the member 33 being then rotated upon its axis to position the abutments 35, and the abutments 37 in line, the member 33 being 5 pressed outwardly by the spring, and said abutments serving to limit the outward movement of said member, while permitting inward movement of said member to compress said spring. The roller engaging end 10 of the member 33 is curved to conform to the curvature of the roller B as indicated at 38, the curved face 38 being disposed with reference to the abutments 37 so that when the curved face of the member is in engagement with the roller, rotation of the member 33 with reference to the pocket 31 is prevented, so that the transmitting member 33 cannot be detached without removal of the roller B. The centering mechanism at the 15 opposite end of the housing is of exactly similar construction to that just described and the parts of the same will be designated by the same numeral which denote the parts of the centering mechanism C just described. 20 25 In operation upon movement of the anti-friction element B to one side or the other of central position, one or the other of the transmitting elements 33 will be carried therewith depending upon the direction of movement of said element, causing the same to move inwardly into the pocket and compress the spring, while the transmitting member at the opposite end of the housing will be held from following the roller by 30 engagement of the abutments 35—35 and 37—37, and when load is removed from the roller B the compressed spring will urge the associated transmitting member 33 outwardly which will return the roller toward central position. When it is desired to 35 disassemble the bearing to renew the springs, or for any other purpose, the roller B may be pried out of the housing by inserting a bar in an opening in the housing, and the 40 transmitting members 33 rotated upon their axes so as to move the abutments out of engagement, after which the transmitting members may be withdrawn from the pockets 31—31. In reassembling the device, the 45 springs are placed in position, and the abutments 37—37 upon each member 33 inserted through the gaps between the abutments 35—35, and subsequently rotated to bring the abutments into engagement, after which the roller is placed in position, the curved 50 faces 38 of the members 33 preventing rotation of the transmitting members which would accidentally release the same.

By the above described arrangement it 60 will be observed that an anti-friction bearing is provided which may be quickly assembled and disassembled, to renew the parts, or for repair, and it also should be noted that the roller is resiliently retained 65 in the housing when free from load due to

the fact that the transmitting members engage the same above the central axis thereof.

While I have herein shown and described what I now consider the preferred manner of carrying out the invention, the same is 70 merely illustrative, and I contemplate all changes and modifications that come within the scope of the claims appended hereto.

I claim:

1. In an anti-friction bearing element, the 75 combination with a housing provided with a bearing plate and a spring pocket at each end, the mouth of each pocket being contracted and providing spaced abutments; of a transmitting member slidably mounted in 80 each of said pockets, each transmitting member having spaced abutments adapted to cooperate with the abutments on said bearing portions to limit inward movement of said transmitting members, said abutments being attachable and detachable by 85 relative rotation of said transmitting members with respect to said bearing pockets; yieldable means interposed between each of said transmitting members and the related 90 bearing pocket; and an anti-friction element disposed between said transmitting members, the portions of said transmitting members engaging said anti-friction element being curved so as to prevent rotation of said 95 members to disengage said abutments while said roller is in operative position.

2. In an anti-friction bearing, the combination with a housing provided with a bearing plate and a spring pocket at each end, 100 the mouth of each pocket being contracted to provide spaced abutments; of a cup shaped transmitting member slidably mounted in each of said pockets, each transmitting member being provided with spaced abutments cooperating with the abutments on said pockets to limit inward movement of said transmitting members, said abutments being attachable and detachable by relative rotation; a coiled spring disposed in each 110 of said pockets and in the cup shaped transmitting member; and an anti-friction element disposed between said transmitting members.

3. In an anti-friction bearing for railway 115 cars adapted to co-operate with opposed bearing surfaces on the truck and body bolsters thereof, the combination with an anti-friction element interposed between said opposed bearing surfaces and having a 120 curved bearing surface co-operating with said opposed bearing surfaces; of means for centering said anti-friction element, including movable followers between which said anti-friction element is interposed; spring 125 means for yieldingly opposing movement of said followers; means for detachably anchoring said followers to one of said bolsters for limited sliding movement, including aligned interengaging anchoring elements 130

on said followers and last named bolster disengageable when rotated in a predetermined direction relatively to each other out of alignment, said followers having curved bearing surfaces interfitting with the curved bearing surface of said anti-friction element, and holding said anchoring elements

against movement in said predetermined direction to maintain the same anchored to the bolster.

In witness that I claim the foregoing I have hereunto subscribed my name this 3rd day of February, 1926.

WILLIAM A. GEIGER.
